UNITED STATES PATENT OFFICE.

WILLIAM L. CALDWELL, OF CANTON, OHIO, ASSIGNOR, BY MESNE ASSIGNMENTS, TO UNITED ALLOY STEEL CORPORATION, OF CANTON, OHIO, A CORPORATION OF NEW YORK.

METALLIC FLUME.

Application filed November 17, 1919. Serial No. 338,697.

To all whom it may concern:

Be it known that I, WILLIAM L. CALDWELL, a citizen of the United States, residing at Canton, in the county of Stark and 5 State of Ohio, have invented a new and useful Metallic Flume, of which the following is a specification.

The invention relates to improvements in metallic flumes in which a thin metal trough is used for conveying water for irrigation or similar purposes, the metal trough being formed of successive sections of proper curvature and joined together to form a continuous channel. To facilitate 10 erection of flumes of this character the joints between the several sections should be made with a minimum of separable parts and without rivets or bolts, and to provide a water tight joint between the several sections, means should be provided for clamping the overlapped ends of the sections tightly together. The joints should further add a certain amount of circumferential 15 stiffness to the thin shell of the flume sections and should be made water tight without the use of solder or the like.

The objects of the invention are to provide a flume with a water tight joint without the use of rivets, bolts or solder; to provide a joint between the flume sections in which no outer clamping bar or inner pressure bar is used; to provide a joint between the flume sections having interior means for forcing the parts into position thus aiding 20 materially in assembling the flume and preventing displacement of the parts by strains placed thereon; to provide means for circumferentially stiffening the structure; to provide a flume having an integral pressure member and an integral clamping member; and to generally improve and simplify the construction of sheet metal flumes.

The above objects are attained by providing a sheet metal flume made up of semi-circular sections, the sections being provided at their ends with external stiffening flanges and with peripheral corrugations or ribs arranged to nest within each other, the corrugated end of one section being nested within the corrugated flanged end of the adjacent section and clamped by providing a structural iron hanger which engages the edges of the interlapped end and is provided with means for drawing the 25 outerlapped end against the interlapped

end, means being provided upon the hanger for forcing the corrugation of the inner section into tight engagement with the corrugation of the outer or flanged section.

The invention thus set forth in general 60 terms is illustrated in the accompanying drawings forming part hereof, in which—

Figure 1 is a perspective view of portions of two sections of flume showing the joint.

Fig. 2 is a plan view of portions of two sections of flume at the joint.

Fig. 3 is a view similar to Fig. 2 of a slightly different arrangement of flume sections.

Fig. 4 is a transverse sectional view through the joint of the flume sections.

Fig. 5 is an enlarged sectional view showing the function of the locking tongue.

A practical embodiment of the invention 75 is disclosed in the accompanying drawings, forming a part of this specification in which similar numerals of reference indicate corresponding parts throughout the several views.

Circumstances often require the construction of flumes of considerable length, the flume being supported at a considerable distance above the ground, it often being necessary to conduct water across a valley and at the same time maintain the proper level and inclination of the flume in order that the water may be carried over elevations. This requires the erection of a trestle or other frame work which is of considerable height 80 at some points while at other points the frame work may be comparatively near the ground, suitable hangers 1 being carried by the frame work for supporting the flume.

The flume sections 2 (Fig. 2) or 2^a and 2^b (Fig. 3) are preferably formed of sheet metal of semi-circular cross section, the sections 2 being made universal, each section having at one end an outwardly pressed corrugation or bead 3 arranged to be nested within a similar outwardly pressed corrugation 4 upon the adjacent end of the next adjacent section, an integral external stiffening flange 5 being formed adjacent to the corrugation 4. Each section 2 is thus provided at one end with an external corrugation or rib 3 and at its other end with a corrugation or groove 4 and with an external stiffening flange 5.

Referring to the construction shown in Fig. 3 the flume sections 2^a and 2^b alternate 110

throughout the length of the flume, each of these sections, as are also the sections 2 being of suitable length to permit of their being easily handled and erected. The sections 2^a as well as the sections 2^b are formed the same at both ends, each section 2^a being provided at each end with the external corrugation or rib 3 and each section 2^b being provided at each end with the external corrugation or groove 4 and with an integral stiffening flange 5. Each section of the flume is thus circumferentially stiffened at each end.

With the provision of the corrugations 3 and 4 and the stiffening flange 5 at each joint of the overlapped ends of adjacent sections, the usual inner pressure bar and outer clamping bar at the joint are unnecessary, the overlapped ends of the flume sections being thus integrally stiffened and reinforced sufficiently to obviate the use of supplemental strengthening means.

The hanger 1 is preferably formed of channel iron as illustrated in the drawings 25 and the flume sections are clamped thereto by means of the clamping bolts 7 which are riveted or otherwise connected at their lower ends to the stiffening flange of the flume section, these clamping bolts extending through suitable apertures in the hanger, nuts 8 being provided thereon for drawing the flume sections toward the hanger and into tight engagement with each other at their overlapped ends.

35 The hanger is provided with means acting against the side or edge portions of the corrugation 3 in the innerlapped end and forcing them directly outward against the side or edge portions of the corrugation 4 in the overlapped end.

Preferred means for the purpose are the flexible locking lugs 9 which may be tongues stamped from the web plate of the hanger whence they extend downward and inward 45 at such an angle that their ends will stand fully inside of the corrugation 3 when the parts are assembled as shown by full lines in Fig. 5.

50 After assembling the parts thus described in detail the nuts 8 are first tightened on the clamping bolts so as to draw the outerlapped end snugly against the innerlapped end with the edges thereof in abutment with the under side of the hanger. 55 The locking lugs are then driven upward by means of a hammer or other suitable tool until their free ends wedge against the inner side of the corrugation 3 near the ends or edge portions thereof; and force them directly against the ends or edge portion of the corrugation 4 in the overlapped end.

60 The bolts are then further tightened so as to clamp the outerlapped end of the one flume section against the innerlapped end of the other flume section, such clamping action

being accomplished by strength of the circumferential flange 5 and the corrugation 4 operating against the corrugation 3 as an abutment.

There is no clamping action of the bolts 70 at the sides of the flume adjacent to the hanger, because the pull of the bolts is substantially parallel with the end portions of the corrugation 3; but the action of the locking lugs positively presses the ends of 75 the pressure bar outward so as to clamp the edge portion of the overlapped ends of the flume sections between the end portions of the corrugation 3 and the abutment formed by the end portions of the circumferential 80 flange, which is stopped against lateral movement by the clamping bolts.

Thus the overlapped ends of the flume sections are clamped together at the sides 85 as well as at the bottom of the flume; and it is evident that when the tongues 9 have been driven upward to effect the clamping action thus described, they will be locked in such position by their wedging action 90 against the corrugation 3 as well as by a biting into the same.

The entire structure is stiffened circumferentially by means of the corrugations 3 and 4 and the stiffening flange 5 upon the flume sections, the joint between the sections 95 being braced by reason of the co-action between the corrugation 3 and the corrugation 4 and stiffening flange 5, no inner pressure bar or outer clamping bar being necessary 100 with this construction as the corrugation 3 acts as an integral pressure bar, while the corrugations 4 and stiffening flange 5 replace the usual outer clamping bar, forming an integral clamping means for drawing the outer section tightly against the inner section. 105

For the purpose of further assuring a water tight joint between the sections of the flume a mastic may be applied to the joints between the sections. This mastic 110 may be what is known to the trade as "gilsomite," and when placed in the joints of the flume sections forms a water tight seal between the sections obviating any leakage 115 of the flow of water through the flume at the joints.

Reference is made to my copending applications, Serial No. 338,695, Serial No. 338,696 and Serial No. 338,698, which contain claims to subject-matter which is related to that which is set forth in the claims made in this application, as follows.

I claim:—

1. A metallic flume including adjoining sections having overlapped ends, a transverse hanger adjacent to the edges of the overlapped ends, external integral stiffening means on the overlapped end and a peripheral corrugation on the innerlapped end 125 abutting the hanger and means on the ends 130

of the external stiffening means for clamping the overlapped end against the innerlapped end.

2. A metallic flume including adjoining sections having overlapped ends, a transverse hanger adjacent to the edges of the overlapped ends, external integral stiffening means on the overlapped end and a peripheral corrugation in the innerlapped end abutting the hanger, a peripheral corrugation in the outerlapped end receiving the corrugation in the innerlapped end, and means on the ends of the external stiffening means for clamping the overlapped end against the innerlapped end.

3. A metallic flume including adjoining sections having overlapped ends, an external flange on the outerlapped end, a transverse hanger adjacent to the edges of the overlapped ends, an external rib upon the innerlapped end abutting the hanger, an internal groove upon the outerlapped end receiving said rib and means for drawing the external flange toward the hanger and clamping the overlapped end against the innerlapped end.

4. A metallic flume including adjoining sections having overlapped ends, an external flange on the outerlapped end, a transverse hanger adjacent to the edges of the overlapped ends, a peripheral corrugation in the innerlapped end abutting the hanger, a peripheral corrugation in the outerlapped end receiving the corrugation in the inner-

lapped end, flexible lugs on the hanger for 35 forcing the inner corrugation outward at the sides of the flume and means for drawing the ends of the flange toward the hanger for clamping the overlapped end against the innerlapped end. 40

5. A metallic flume including adjoining sections having overlapped ends, a transverse hanger adjacent to the edges of the overlapped ends, means abutting the hanger and staying the innerlapped end against external pressure, and means clamping the overlapped end against the innerlapped end, there being outwardly directed tongues struck downward from the transverse hanger inside the ends of the staying means 45 of the innerlapped end and wedged upward against the same to press them outward. 50

6. A metallic flume including adjoining sections having overlapped ends, a transverse hanger adjacent to the edges of the overlapped ends, a peripheral corrugation abutting the hanger and staying the innerlapped end against external pressure, and means clamping the overlapped end 55 against the innerlapped end, there being 60 tongues struck from the transverse hanger extending downward and outward and being driven upward to impinge the inner sides of the staying means and to force and lock the same outward against the outer 65 lapped end of the flume section.

WILLIAM L. CALDWELL.
